SOCKET FOR TUBULAR LAMPS

Kurt Wiegand, Hohenneuendorf, near Berlin,
and Alexander Koenig, Berlin-Charlottenburg,
Germany, assignors to General Electric Com-
pany, a corporation of New York

Application December 8, 1936, Serial No. 114,844
In Germany December 18, 1935

4 Claims. (Cl. 173—328)

The subject of this invention is a contact-proof holding means for tubular or strip-light lamps having two bases, each of the bases consisting of a metal disk of a small width sealed to the lamp bulb. The invention has for its purpose to provide sockets into which the tubular lamp may be readily inserted and secured and also switched into and out of circuit, said sockets having only a small width dimension, so that no disturbing interruptions in the continuity of the line of light will occur between the adjacent tubular lamps when arranged in one direction behind each other.

The drawing shows a socket according to this invention in a physical embodiment.

Fig. 1 shows in perspective the main parts of an individual socket with the parts separated; Fig. 2 shows the individual socket in a cross section; Fig. 3 shows it in a longitudinal section; Fig. 4 shows the locked position of the socket and of the base in cross section, and Fig. 5 shows another design of a detail of the socket in cross section.

Each individual socket consists, as shown particularly in Fig. 1, of a body 1, an insulating housing 2, an annular insulating sleeve 3 and a back plate 4. The socket body 1 has, as usual, a contact 5 to which the current conductor 6 is connected. By means of screws (not shown) which are countersunk, the body 1 can be fastened to a base plate (wall, board or the like). The insulating housing 2 is provided with a contact clamp 7 to which a contact pin 8 is connected by means of a leaf spring 7'. An upwardly-directed wall 9 is integral with part 2 or fastened, as by means of screws (not shown) entering from below. In the wall 9, a cylindrical opening 10 is provided which is partly open on top as a result of the cut-out 11 whereby the base of a lamp may be entered transversely therein. An annular groove 12, in which the contact pin 8 extends, is provided in the cylindrical uncut periphery or opening 10. The annular sleeve 3, which is provided with a corresponding cut-out 15, is placed in the opening 10 and is held in the wall 9, so that it can be rotated, by means of its rimmed end wall 13 which fits in a groove 14 (Fig. 3) of the wall 9. It is prevented from displacement in axial direction by means of the back plate 4 which can simply be screwed to the wall 9. The limitation edges of the annular sleeve 3, which are formed by the cut-out 15, are indicated by 16 and 17 (Fig. 1). The housing 2 can be fastened in a known manner by means of screws (not shown) to the body 1.

The construction of the base 18 of the tubular

lamp 19, which is to be secured in such sockets, is also shown in Fig. 1. The disk-shaped metal base 18 has on its flanged edge two projections 20, 21 and one radial contact projection 22 which is bent somewhat and which, in its center, has a small indentation 23.

Before placing the lamp in the socket, each annular sleeve 3 must be adjusted within its wall 9, in such a way that its cut-out 15 coincides with the cut-out 11 of the wall 9; in other words, in such a way that the two cut-outs are directed upward, using the position of the socket according to Fig. 1 as a basis. The disk-shaped lamp bases 18 can then be inserted without difficulty when the position of the lamp 19 is parallel to the axis of the socket. After the insertion of the lamp, the edge projections 20, 21 of each base will lie against the end edges 16 or 17 of the annular sleeve 3, so that when the lamp is subsequently rotated in either direction, the annular sleeve will be taken along. The lamp is then turned by about 180° until the contact element 22 of the base which protrudes through the cut-out 15 in the sleeve, arrives with its indentation on the elastic contact pin 8 of the socket housing, which in that case not only establishes the current supply to the lamp, but also holds it elastically as it snaps into the indentation 23 of the base projection 22. The lamp may be switched out of circuit by partial rotation thereof. In the closed circuit position, the cut-out 11 of the wall 9 is covered by the cylindrical part of the annular sleeve 3, so that the lamp cannot be removed from the socket. If the lamp is to be removed from the socket, then a rotation by 180° in one direction or the other will suffice again, in which case the annular sleeve 3 will again be taken along by the projections on the base edge 20 or 21 until the latter are free to move in an upward direction in the cut-out 11 of the wall 9, whereupon the lamp can be removed quite readily. In addition to the turning of the lamp, no other manipulation thereof is required for its insertion in, and removal from, the socket. Also all electrically charged parts are protected at all times against personal contact.

In the modified construction of the individual socket according to Fig. 5, the contact and blocking pin 8 will be energized only when it is moved in a backward direction by the base projection 22. For this purpose, the contact pin is supported, through the intermediary of a supporting spring 24, on an insulated base plate 25 through which the contact spring 7' extends. The contact pin 8, as a result, will not be energized

in the unloaded state, while a voltage will be applied only when the base projection 22 pushes it backward to such an extent that its free lower end will come in contact with the spring 1'.

5 What we claim as new and desire to secure by Letters Patent of the United States is:

1. A holder for an end of a double base lamp comprising an insulating wall member having an annular opening with a cut-out portion and an annular groove opposite said cut-out portion, 10 a terminal contact located in the bottom of the groove of said wall member, an insulating sleeve rotatable in said annular opening and provided with a corresponding cut-out portion, and said lamp base having a disk-shaped base provided 15 with a contact projecting from the periphery thereof into said groove of said wall member whereby rotation of the lamp effects closure of the cut-out in the wall member and closure of the circuit thereof.
- 20 2. A holder for one end of a double base lamp comprising an insulating wall member having an annular opening with a cut-out portion, a terminal contact located in the uncut portion thereof, an insulating sleeve rotatable in said annular opening and having a corresponding cut-out portion with transverse shoulders formed at

the ends thereof, and said lamp base provided with a radial contact, also edge projections adapted to engage the transverse shoulders of said sleeve upon being inserted through said cut-outs.

3. A holder for one end of a double base lamp 5 comprising an insulating wall member having an annular opening with a cut-out portion at the upper part thereof and a groove in the lower part thereof, a spring-pressed contact located in said groove, an insulating sleeve with an end 10 wall and a corresponding cut-out rotatable in said annular opening, and said lamp base having a radial contact movable rotatably in said groove into engagement with said contact.

4. A holder for one end of a double base lamp 15 comprising a wall member having an annular opening extending therethrough and a portion cut-out to permit the lamp base to enter, a contact located in the annular opening opposite said cut-out, an insulating sleeve provided with an 20 end flange to abut the outer surface of said wall member and a corresponding cut-out adapted to rotate in said annular opening, and a retaining plate secured to said wall member over the end of said sleeve. 25
